Air Force Base, Ohio

Application November 28, 1949, Serial No. 129,862

5 Claims. (Cl. 137—512.1)

(Granted under Title 35, U. S. Code (1952),
sec. 266)

1

The invention described herein may be manufactured and used by or for the Government for governmental purposes without payment to us of any royalty thereon.

This invention relates to pulse jet motors of the acoustically tuned resonant frequency types, and more specifically to improved check valve means for introducing the combustion mixture into the combustion chambers of resonant pulse jet motors, having for an object an improved valve structure for shortening or substantially eliminating the delay between air and fuel movement reversal and the valve actuation thereby in resonant pulse jet motors.

Another object of the invention is the provision of improved fuel mixture inlet valve means for resonant pulse jet motors, incorporating means for increasing the accelerating action of the fuel inlet valves that are normally closed by the combustion chamber pressure head and opened by the reduction of combustion chamber pressure and fuel mixture inflow into the combustion chamber.

A further object is the provision of resilient actuator means for the valves which are separate from the valves, for converting the kinetic energy of the valves incident to movement thereof into deformation of the actuator means, and then utilizing this kinetic energy to accelerate the return movement of the valves to their opposite positions.

A still further object is the utilization of resilient actuator means for accelerating the movement of the fuel inlet valves in one direction and then accelerating the movement of the valves in the opposite direction in a substantially tuned resonant frequency relative to the tuned combustion pulse jet cycle frequency.

A further object is the provision of resilient actuator means located at opposite sides of the fuel mixture inlet check valves having a predetermined tuned frequency which is substantially similar to the tuned resonant frequency of the pulse jet cycles of the motor for decelerating the movement of the valves in one direction and accelerating the valve movement in the opposite direction incident to impingement of the valves against the resilient actuator means, thereby obtaining faster and more efficient valve actuations for improving the efficiency and operation of the resonant pulse jet cycle of a pulse jet motor.

Other objects and advantages of the invention will appear from the following description, taken in connection with the accompanying drawing

2

in which like reference characters refer to like parts in the several figures:

Figure 1 is a somewhat diagrammatic side elevation of a resonant pulse jet motor incorporating the invention, parts thereof being broken away and shown in section;

Figure 2 is an enlarged, fragmentary vertical sectional view on line 2—2 of Figure 1 of one form of the invention, illustrating our improved cup shaped fuel inlet control valves in their closed positions in full lines, and in open positions in dotted lines;

Figures 3 and 4 are fragmentary vertical sectional views illustrating a modified embodiment of cup shaped check valve and valve seat arrangement, incorporating resilient valve actuators having a predetermined tune frequency for accelerating the check valve movement toward each of their opposite positions and then decelerating the valve movement, Figure 3 illustrating the valves in their closed position with the lower spring actuators under tension and ready to accelerate the opening movement of the valves, while Figure 4 shows the upper resilient actuators tensioned, following the accelerated valve return movement, and ready to accelerate the return movement of the valves to their closing positions, as shown in Figure 3.

Referring to Figure 1 of the drawing, the reference numeral 1 denotes an acoustically tuned resonant frequency pulse jet motor having a combustion chamber 2, a discharge or tail pipe 3 with a discharge outlet 4 opening into a concentrically arranged venturi nozzle 5. A check valve unit 6, incorporating our improved check valve structure is secured across the base fuel mixture opening 7 in the combustion chamber 2, a downwardly tapered air and fuel inlet mixing tube 8 being secured across the lower facet of the valve unit 6. The tube 8 is formed with an outwardly flared mouth or venturi opening 9 and a fuel jet 10 is supported in the venturi 9 by a suitable spider, with its fuel jet opening located directly below a deflecting, or back pressure, preventing baffle 11, carried by the tube 8 on supporting arms. A fuel tank 12 is connected to a carburetor 13 by a pipe 14, supplying fuel through a shut off valve controlled conduit 15 to the fuel jet nozzle 10. This arrangement discloses a simple form of resonant pulse jet motor, for illustrative purposes, in which our improved check valve structure 6 is incorporated. A compressed air jet 16, supplied from a high pressure air source, not shown, and controlled by a shut-off valve 17 may be provided for initiating the pulse

jet cycle in the conventional manner by directing a jet of air through the venturi 9 to withdraw fuel from the fuel jet 10 and inject the air and fuel combustible mixture through our improved check valve structure with minimum resistance into the combustion chamber 2 to form an explosive mixture therein. The explosive mixture thus introduced is initially ignited in any conventional manner, such as by a spark plug 18 which is supplied with high tension current from a spark coil 19, upon closing of the switch 20 connected to the current source or battery 20^a. When the pulse jet motor is started the inertia of the rapidly ejected exploded gases moving through the tail pipe 3 finally creates a low pressure area or partial vacuum within the combustion chamber, causing the flow of a fresh explosive charge through the check valve plate 6. The partial vacuum now created in the combustion chamber causes a rapid return of the later portion of the previously ejected hot gases entering the tail pipe to return back into the combustion chamber, causing a rapid increase in pressure within the combustion chamber, producing some compression of the fresh gaseous fuel mixture introduced therein. The returned hot gases and the hot condition of the combustion chamber cause the ignition and explosion of the fresh gases and the resonant pulse jet cycle is then repeated and continued very rapidly. The spark ignition means and the air blast jet are turned off after the starting, since they are no longer needed.

It is conventional to use thin leaf spring closure valves in resonant pulse jet motors to control the fuel and air intake ports, but since these valves open under spring tension and also close because of the spring tension, and are flat, they must be made strong and therefore must be stiff, in order to withstand the explosion forces within the combustion chamber. A material pressure reduction within the combustion chamber is therefore necessary to open these conventional leaf spring valves and this tension, plus the inertia of the valves, causes a somewhat late opening action. The spring tension of the conventional leaf spring valves also cause them to close early, or before the combustion chamber pressure changes from a positive to a negative pressure value. These conditions reduce the relative possible length of time of the fuel mixture introduction period and consequently reduce the possible efficiency of conventional pulse jet motors, also limiting the rate or possible number of pulses per unit of time that can ordinarily be obtained.

By employing our improved valve arrangement, utilizing circular, very thin self sustaining cup shaped valves, each having a somewhat spherical contour, as disclosed in Figures 2 to 4, and forming them of suitable very thin tempered sheet material, and utilizing supporting and valve retainer plates positioned horizontally in vertically spaced relation to each other below and above the valves with aligned valve seats and protuberances facing each other, formed with surface contours similar to the valve surface contours and having fuel inlet openings therethrough as shown more particularly in Figure 2, it is possible to greatly improve the efficiency of resonant pulse jet motors.

In Figure 2 the cup shaped valves are indicated at 21, being preferably stamped from very thin suitable metallic alloy stock, tempered and formed with substantially spherical interior and

exterior contours. The valves 21 seat in complementary shaped depressions 21^a formed in a valve supporting plate 22 having fuel inlet passages 22^a passing centrally therethrough. A valve retainer plate 23 extends across the entrance to the combustion chamber 2 in superimposed spaced relation to the supporting plate 22, the cup shaped valves 21 being freely movable vertically therebetween. The retainer plate 23 is preferably formed of thin sheet metal stock by stamping and is foraminous, having a multitude of small fuel inlet apertures 24 therethrough. The plate 23 is also formed with downwardly projecting spherical protuberances 25, each having a spherical contour shaped to fit the interiors of one of the cup shaped valves 21. The valves 21 are free to move between the supporting and retainer plates 22 and 23 and fit either the protuberances 25 or the depressions 21^a.

Immediately upon reduction of pressure within the combustion chamber 2 the valves 21 will unseat and float upwardly on the incoming fuel and air mixture passing through the inlet openings 22^a toward the combustion chamber 2, the valves 21 being retained against the retainer plate 23, and on the protuberances 25, deflecting the gases laterally through the many openings 24 in foraminous plate 23, and are actually held up against the plate 23 by the suction within the combustion chamber which is effective through the apertures 24 that are covered by the surface of the valve, as illustrated in dotted lines in Fig. 2.

Following the fuel intake cycle and the return of the gases through the tail pipe 3 into the combustion chamber 2, the pressure within the combustion chamber 2 increases from negative to a positive pressure and the valves 21 freely drop to their closed positions on the supporting plate 22, closing the intake opening 22^a, as shown in full lines in Figure 2.

Since the valves are very thin, light, and are free to move, there is a minimum time delay between either of their movements (from closed to open position, or from open to closed position) and their movement can be very rapid, permitting more fuel to enter during a relatively longer opening and closing cycle, permitting faster tuned resonant pulse jet action.

In order to further improve the valve actuation, as illustrated in the modified embodiment in Figures 3 and 4, a valve supporting plate 22^b is provided, having enlarged circular depressions 26 formed therein with central fuel inlet passages 22^c connecting the depression 26 with the space below the valve unit.

An upper or valve retainer plate, as indicated at 23^b, is provided which is somewhat thicker than the plate 23 in Figure 2. The retainer plate 23^b is provided with downwardly extending short posts, standards, or spring supporting means, located concentrically of the enlarged depressions 26. Intermediate the posts 27, the plate 23 is formed with fuel inlet ports 24^b of sufficient area in the aggregate to permit the free passage of any fuel mixture passing through the apertures 22^c in the valve supporting plate 22^b. Located on each of the posts 27, in parallel spaced relation to the lower surface of the retainer plate 22^b, is a thin tempered resilient valve return disk 28, the disks 28 having diameters exceeding the diameters of the cup shaped valves 21.

A thin resilient tempered valve return plate

or sheet 29 is secured across the upper surface of the valve supporting plate 22^b. The plate 22^b is formed with circular openings 30 therethrough, each opening being disposed concentrically to the depressions 26, and the fuel inlet ports 22^c, each opening 30 having a diameter somewhat less than the diameter of the cup shaped valves 21. The thickness and resiliency of the valve spring return plates and disks 29 and 28 are important, also the relative "over hang" or extension of the plugs or the periphery of the disks beyond the edges of the depressions 26 and beyond the supporting posts 27. The pulse jet resonant cycles of the pulse jet motor are tuned, of course, in the conventional manner, by properly proportioning the length and diameter of the tail pipe 3 relative to the area of the combustion chamber 2 to produce the desired resonant pulse jet frequency. Within limits, the shorter and larger the tail pipe, the more rapid are the resonant pulse jet cycles. Making the tail pipe longer, and/or smaller reduces the resonant frequency of the pulse jet cycles. When using a very high resonant frequency the resilient spring portions of the valve return or actuator plates are proportioned, relative to their thickness, "over hang" and the kind of material used, so as to be tuned to the resonant frequency of pulse jet cycle employed.

After the first explosion within the combustion chamber 2 takes place, the spring actuators 29 and 28 operating at their corresponding natural frequency, equal to the resonant pulse jet frequency, will toss the thin light cup shaped valves 21 back and forth between their open and closed positions, permitting a faster valve actuation than would be the case if the tuned resilient valve actuators were not used. Since the movement is faster a better fuel inlet cycle is obtained. As the explosion occurs in the combustion chamber 2 the cup shaped valves 21 are forced downwardly tensioning the overhanging portion of the lower spring plate 29 which surrounds the valve seat and fuel opening 30 therein. The resilient action of the plate, as the exhaust cycle ends, quickly tosses the valve 21 against the upper spring disk 28, and assisted by the partial vacuum in the combustion chamber, the upper disk 28 is tensioned as illustrated in Figure 4. When the neutral pressure in the combustion chamber quickly follows, the spring disks 28 quickly tosses the cup shaped valves 21 against the lower valve return plate 29, about the time that the explosion occurs, causing the portion of plate 29 surrounding the valve as seen in Figure 4 to be tensioned and the cycle is repeated.

What we claim is:

1. An inlet valve construction comprising a valve supporting plate having a plurality of valve receiving depressions formed in its topside, having inlet openings extending through the plate in communication with the valve receiving depressions at the centers thereof; a valve retainer plate fixed in parallel spaced relation above the topside of the valve supporting plate, having valve engaging projections thereon facing toward the valve receiving depressions in substantially axial alignment with the centers of the valve receiving depressions and formed with a plurality of outlet openings extending therethrough from the space between the valve supporting and retainer plates; lightweight cup-shape thin walled valves disposed intermediate the valve receiving depressions and the aligned valve engaging projections for free oscillatory movements between the support-

ing and retainer plates, said valves being formed with outer and inner spherical contour surfaces for seating respectively in the valve receiving depressions, and on the valve engaging projections and leaf spring means carried by each of the valve engaging projections in spaced relation to the valves when seated in said depressions and projecting into the path of movement of each valve toward the valve engaging projections to be tensioned thereby upon movement of the valve toward the valve engaging projections to assist in return of the valves toward the valve receiving depressions.

2. An inlet valve unit comprising an inlet valve supporting plate having an upper surface and an upwardly extending annular supporting flange projecting therefrom, said upper surface having a plurality of inlet valve receiving depressions formed therein with inlet passages extending from the bases of the depressions through the plate; a valve retainer plate seated on the supporting flange in parallel spaced relation to the upper surface of the valve supporting plate; resilient valve engaging means projecting toward the valve receiving depressions in the valve supporting plate and substantially axial alignment with the centers of the depressions, each resilient valve engaging means comprising a supporting standard projecting from the retainer plate toward the center of one of the valve receiving depressions and a thin flexible resilient valve actuator disc fixed on the supporting standard in substantially parallel spaced relation to the valve retainer plate, said disc having a diameter slightly greater than the diameter of the valve to be used; a thin resilient valve retainer and actuator plate disposed in parallel relation to the upper surface of the valve supporting plate and extending at least partly across the valve receiving depressions in spaced relation to the bottoms of the depressions; said resilient retainer and actuator plate having circular valve receiving openings extending therethrough in concentric alignment with the centers of the valve receiving depressions; said openings being smaller than the diameter of the valves to be used; rigid thin walled cup-shape valve members, each having a circular rim facing toward one of said resilient actuator discs near its periphery, for impingement with the resilient disc near its periphery incident to movement of the valve members toward the retainer plate, said valve members each having a substantially spherically curved lower surface intermediate its rim and facing the resilient valve supporting plate for impingement with the resilient supporting plate at the edge of the circular valve receiving openings therethrough, incident to movement of the valve members into the valve receiving depressions to close the openings and tension the resilient supporting plate portion in the depressions surrounding the valve receiving openings for projecting the valves toward the resilient actuator discs upon reverse valve movement.
3. Apparatus as claimed in claim 2 in which the resilient actuating portions of the discs and the resilient valve supporting portions of the resilient valve supporting plate are resiliently tuned to a predetermined vibration frequency.
4. In a fuel and air inlet valve construction for a resonant pulse jet engine; a valve supporting plate having valve receiving depressions in one side thereof; an apertured valve retainer plate disposed in parallel spaced relation to the valve supporting plate, next to the side thereof

having the valve receiving depressions therein, said valve supporting plate having inlet ports extending therethrough in communication with the interior of the valve receiving depressions; cup-shape valve elements freely movable in both directions between the retainer plate and the depressions in the supporting plate, between positions in the depressions closing the inlet ports and positions out of the depressions opening the inlet ports; spring means carried by the supporting plate in spaced relation to the valve elements when moved toward the retainer plate and projecting into the path of inlet closing movement of the valves to be tensioned thereby for projecting the valves when seated in the depressions toward the valve retainer plate; and spring means carried by the retainer plate and positioned in spaced relation to each of the valve elements when the same are in engagement with the first mentioned spring means and projecting into the path of inlet opening movement of the valves to be tensioned thereby incident to valve movement away from said valve receiving depressions for projecting the valves toward the valve receiving depressions, said spring means having a predetermined tuned vibration frequency.

5. An inlet valve construction for the fuel mixture inlet of a resonant pulse jet engine having a combustion chamber and communicating tail pipe tuned to a predetermined resonant pulse jet cycle frequency; said valve construction comprising a valve supporting plate having enlarged valve receiving depressions formed in the upper surface thereof and inlet passages extending through the plate in communication with the bases of the depressions; a valve retainer plate disposed in spaced parallel relation to the supporting plate and carried thereby, having outlet passages therethrough, spring supporting posts extending from the valve retainer plate in axial alignment with the centers of the valve receiving depressions; resilient valve actuator spring members carried at the ends of the posts and projecting laterally over the valve receiving depressions; cup-shape valves each having a circular rim portion facing the valve retainer plate and disposed to move into impinging engagement with the spring members to tension the same; said valve members each having a convex

5 spherical contour portion intermediate the rim portion facing the valve receiving depressions and adapted to move thereinto, and having a concave interior contour to receive the posts therein upon movement of the rim portion of the valve into impinging engagement with the spring members; a thin resilient valve seating and actuator plate disposed in juxtaposed relation to the surface of the supporting plate having the depressions therein, said actuator plate projecting outwardly from the edges of the depressions to form resilient valve seats therein comprising annular circular openings for seating the convex spherical contour portions of the valve therein to close the inlet passages and resiliently tension the portion of the plate projecting from the periphery of the valve receiving depressions to the circular opening.
